STOCKING

Richard Ernst Schletter, Oak Lane, Pa.

Application May 17, 1950, Serial No. 9,997

Term of patent 3½ years

(Cl. D47—7)

To all whom it may concern:

Be it known that I, Richard Ernst Schletter, a citizen of the United States of America, residing at Oak Lane, Montgomery County, State of Pennsylvania, have invented a new, original, and ornamental Design for a Stocking, of which the following is a specification, reference being had to the accompanying drawing, forming a part thereof:

Figure 1 is a perspective view of a stocking, embodying my ornamental design, as it appears in use on the leg of a wearer; and

Fig. 2 is a view of the foot portion of the stocking shown in Fig. 1, as it appears in flat form and on an enlarged scale relative to Fig. 1.

I claim:

The ornamental design for a stocking, as shown and described.

RICHARD ERNST SCHLETTER.
